Primary Examiner — Michael A. Pratt*Assistant Examiner* — Kaitlan Walker(74) *Attorney, Agent, or Firm* — Bayramoglu Law Offices LLC(57) **CLAIM**

The ornamental design for a hunting rifle, as shown and described.

DESCRIPTION

FIG. 1 is a top, front perspective view of a hunting rifle showing my new design;

FIG. 2 is a front plan view of a hunting rifle in a folded configuration;

FIG. 3 is a front, bottom perspective view thereof;

FIG. 4 is a front perspective view of a hunting rifle in a second folded configuration;

FIG. 5 is a front perspective view thereof;

FIG. 6 is a bottom perspective view thereof; and,

FIG. 7 is an enlarged top, rear perspective view thereof.

The broken lines depict portions of the hunting rifle that form no part of the claimed design.

1 Claim, 7 Drawing Sheets(56)
